To all whom it may concern:

Be it known that I, ALICE J. DEMPSEY, a citizen of the United States, residing at Washington, in the District of Columbia, have invented and produced a new and original Design for Spoons, of which the following is a specification, reference being had to the accompanying drawing, forming a part thereof, which drawing represents a front or obverse view of a spoon embodying my design.

The leading features of my design consist of a representation of the Administration Building at the World's Fair at Chicago, Illinois, at the end of the handle and an entablature adjacent to said building and containing a globe, and the bowl of the spoon containing a representation of one of the ships of Christopher Columbus.

In the drawing, A is the handle.

B is the representation of the Administration Building at Chicago.

C is the entablature containing the globe.

D is the bowl containing the representation of the Columbus ship.

What I claim is—

The design for a spoon, as shown.

In testimony whereof I hereto affix my signature in presence of two witnesses.
